UNITED STATES PATENT OFFICE.

GENNARO DE PAMPHILIS, OF NEW YORK, N. Y.

PAPER-SCORING DEVICE.

Application filed November 10, 1927. Serial No. 232,225.

This invention relates to devices for scoring, creasing and indenting paper sheets preparatory to folding and more particularly to devices in the form of attachments to machines for shearing and cutting paper, such machines consisting of a base having a platform for the paper, a power driven shear operable thereover and means for clamping the sheets to be cut in an adjusted position on the platform.

The main object of the invention is in the provision of means for utilizing the paper binding beam as a support for the scoring blades and using the machine without change of any kind.

A further feature is to provide a plurality of scoring blades, some with two or more operative edges, or combinations of scoring blades, perforating devices and cutting knives, all being readily attachable to the binder beam, in a manner permitting easy and instant change as may be desired.

These and like objects are accomplished by the novel and practical construction and arrangement of parts hereinafter described and shown in the annexed drawing, forming a material part of this disclosure, and in which:—

Figure 1 is a transverse sectional view taken in a vertical plane through a conventional type of paper cutting machine and illustrating the application of an embodiment of the invention.

Figure 2 is a perspective view showing in separate form the main parts of the device as ready to assemble.

Figure 3 is a perspective sectional view of one of the scoring blades in detail.

Figure 4 is a similar view of another form of blade.

Figure 5 is a plan view of a sheet of tympan paper as scored.

Figure 6 is a transverse sectional view of a combined scoring and knife blade, as used in making paper boxes.

Figure 7 is a bottom plan view of the same.

Figure 8 is a fragmentary perspective view of a paper perforating device interchangeable with the scoring devices.

Referring more in detail to the drawing, the numeral 10 designates in general a hollow cabinet base, such as is customary for paper cutting machines, the mechanism being partially disposed therein.

A projecting shelf-like platform 11 at the front contains a rectangular recess extending

lengthwise from side to side, the same being receptive of an elongated block 12 of wood or other material of a nature not liable to damage the knives or scoring blades which may be brought in contact with it, the block being reversible to permit all four sides to be used and may be readily replaced by another when worn.

The upper part of the machine is open at the top and disposed therein are uprights 13 connected by a bar 14 carrying a series of vertical guides 15, these guides being suited to enter into corresponding slots 16 formed in a cross binder 17 adapted to clamp the paper sheets upon the platform.

Movable across the face of the binder bar 17 is a power operated knife bar 18 carrying a shear blade 19 and guided at the front by uprights 20 at the ends, the same being positioned above the platform side guides 21.

Mounted in the upper portions of the uprights 13 is a shaft 22 having near its ends plate segments 23 over which are trained flexible elements 24, such as chains, the same engaging the binder bar 17 near its upper edge, one end of the chains being fixed to the segments.

Coiled springs 25, fixed respectively to the shaft 22 and segments, operate to maintain the bar 17 in a normally raised position.

Another pair of chains 26, secured to the opposite ends of the segments, and offset with relation to the chains 24, are attached at their opposite ends to brackets 27 reaching up from the binder bar 17 so that the same is substantially counterbalanced by the action of the springs 25.

Extending down from one end of the bar 17, outside the platform, is a vertical bar 28, guided in a bracket 29 at its lower portion and provided with a forwardly extending arm 30 carrying at its end a pivot 31.

The pivot is freely engaged in a slot 32 in the end of a link 33, in turn pivoted to a foot lever 34 fulcrumed on a stud 35 set in a bracket 38 at the front of the base, the foot lever being normally raised by the action of a spring 37 coiled around the stud.

All of the several parts described in the foregoing are elements of a conventional paper cutting machine and in themselves constitute no part of the present invention but are given in order to arrive at a complete understanding thereof.

The invention is composed of an angle bar 40—41 having one or both of its longi-

tudinal edges beveled to produce a creasing or scoring effect upon paper, this bar being held by either of its angles against the lower surface of the binder bar 17.

5 The clamping means consists of a narrow flat plate 42, equal in width to the binder bar 17 and having fixed therein two or more rods 43 suited to pass through appropriate vertical openings in the binder bar and there 10 secured by wing nuts 44.

Obviously by slackening the nuts, the plate 42 may be relaxed, permitting withdrawal or substitution of other scoring bars, such 15 for instance as indicated in Figure 4, in which a three limbed angle is shown, respectively 45, 46 and 47.

As shown in Figures 6 and 7, a combined scoring and shearing cutter is disclosed, the same consisting of a plate bar 48 capable 20 of being clamped by the plate 42 to the binder bar 17, the bar 48 having a connection 49 joining a rectangular plate 50.

The plate 50 has cutters 51 at its four edges, the same extending slightly beyond 25 the scoring edges 52, which in connection with transverse blades, may be operated to produce a paper box blank.

The simplest form of the invention, shown 30 in operative position in Figure 1 is adapted specifically for scoring paper sheets as 55, the same being disposed on the platform 11, their inner edges against the guides 15 and the portion to be creased arranged to register over the wooden block 12.

35 Such sheet 55 is shown in detail in Figure 5, known as tympan paper and is scored, as at 56, to readily permit bending as desired.

It is to be understood that in operation, the 40 paper sheets having been adjusted, the crease is formed by depression of the foot lever 34, causing the scoring beam to descend with whatever force may be necessary.

In addition to the foregoing, other types 45 of paper cutting and perforating dies, may be substituted, as for instance that shown in Figure 8 in which a plate 53 may be clamped to the binder by the element 42, said plate having a row of perforated pins 54 extending downward near its outer edge, the

pins entering a die having conformable 50 openings disposed in place of the block 12, and it will be obvious that dies of other shape may be substituted.

As changes of construction could be made within the scope of the invention, it is intended that all matter contained in the foregoing description or shown in the accompanying drawings shall be interpreted as 55 illustrative and not in a limiting sense.

Having thus described my invention, what 60 I claim as new and desire to secure by Letters Patent, is:—

1. In combination with a paper cutting machine having a platform and a foot operated binder bar thereover, of an angle bar 65 having one or more scoring edges, and means to clamp the bar to said binder bar.

2. In combination with a paper cutting machine having a platform, paper guides at its rear and a foot lever actuated binder bar, 70 of a scoring blade, and means to adjustably secure said blade to the lower surface of said binder bar.

3. In combination with a paper cutting machine having a platform and a binder bar 75 movable thereover, of means for cutting, creasing and scoring paper, and clamp means to engage said device to the under edge of said bar 7.

4. In combination with a paper cutting machine having a platform and a foot operated binder bar thereover, of a bar having 80 two or more scoring edges disposed at right angles one to another, and means to affix said bar to said binder bar in such manner as to 85 extend one of its edges selectively downward.

5. In combination with a paper cutting machine having a platform containing a longitudinal recess, a foot operated binder bar and means to normally raise said bar, of a wooden block reversibly engaged in the recess, a creasing bar having a right angled element, and a clamp plate to hold said element in rigid relation with the under edge 90 of said bar.

In testimony whereof I affix my signature.

GENNARO DE PAMPHILIS.
